CLAIM

The ornamental design for a combination house-shaped container and lip balm, as shown and described.

DESCRIPTION

FIG. 1 is a perspective view of the combination house-shaped container and lip balm;

FIG. 2 is a front side view thereof;

FIG. 3 is a rear side view thereof;

FIG. 4 is a right side view of the combination house-shaped container and lip balm, the left side view being a mirror image thereof;

FIG. 5 is a top side view thereof; and,

FIG. 6 is a bottom side view thereof.

The broken lines illustrate portions of the combination house-shaped container and lip balm that form no part of the claimed design.

1 Claim, 6 Drawing Sheets
